Add or to

The Clothier's Sewing Machine Company of Newark N.J.
Letters Patent No 2474. Dated Oct. 2. 1866

Design for the frame of a Sewing Machine.

The Schedule referred to in these Letters Patent and making part of the same

To all whom it may concern:

Be it known that S. Joseph Bond Junior of Newark Essex County New Jersey have originated and designed a new Pattern of Shape and form for the Skeleton Frame of Sewing Machine Tables, of which the following is a full, clear and exact description, reference being had to the accompanying Photographs therof making a part of this Specification.

A, B, are the Standards. — B, is the connecting brace between them and support for the driving wheel C, — and D, is the treadle.

The peculiarities of the scroll and ornamental work which make upon the several parts, and upon the whole unit, an ornamental design without sacrificing strength as sufficiently indicated by the Photographs without a minute description.

That I claim and desire to have by letters Patent is; The Design for the Skeleton Frame for Sewing Machine Tables herein set forth and shown.

Witnessed

Joseph Bond Jr

Geo. H. Collier

Gustave M. Burge.
